UNITED STATES PATENT OFFICE.

FRANZ KÖHN, OF PLÖN, GERMANY.

LATERAL COUPLING FOR RAILROAD-CARS.

SPECIFICATION forming part of Letters Patent No. 722,114, dated March 3, 1903.

Application filed July 7, 1902. Serial No. 114,649. (No model.)

To all whom it may concern:

Be it known that I, FRANZ KÖHN, piscicul-
turist, a subject of the King of Prussia, German
Emperor, and a resident of Plön, in the
5 Kingdom of Prussia and Empire of Germany,
have invented certain new and useful Im-
provements in Lateral Couplings for Rail-
road-Cars, of which the following is a speci-
fication.

10 This invention relates to a lateral coupling
for railroad-cars and differs from hitherto-
known couplings by the fact that the coupling-hooks
are not arranged to engage with
each other from above, the coupling being
15 effected laterally.

The invention is illustrated in the accom-
panying drawings, in which—

Figure 1 is a view of the improved cou-
pling from underneath the car. Fig. 2 is a side
20 view, while Figs. 3 to 6 are details.

Similar letters refer to similar parts through-
out the several views.

Referring to the drawings, below the car-
frame and in the center of same rods *d* are
25 rigidly attached. These rods have a round
section at their front end and are provided
with longitudinal slots *e*. In these longitudi-
nal slots bolts *a* connect the bifurcated ends
of the coupling-hooks *b*, which at their front
30 ends are wide and of massive construction,
the said bolts being longitudinally movable
in the said slots *e*. Furthermore, with these
bolts *a* slanting U-shaped bent arms *c* are
rigidly attached, so that the latter form, as it
35 were, with the coupling-hooks *b* one rigid
piece. The closed ends of this U-shaped
shackle-arm are connected by means of stiff-
ening-braces *v* of suitable length with the
coupling-hooks *b*. Below the cars are pivots
40 or shafts *i*, upon which the double-arm le-
vers *h h'* turn. The long arms of these le-
vers *h h'* are connected or secured by means
of chains, levers, or wheel-gear with the shaft
45 *o*, extending along the whole width of the car,
the latter shaft being rotatable by means of
cranks from both sides of the car.

The coupling of the car is effected auto-
matically in view of the fact that in the posi-
tion of rest or uncoupled position the two

coupling-hooks *b* are opposite to each other, 50
from which it will be apparent that upon the
concussion of the hooks the slanting surfaces
l of the same will glide upon each other and
by engaging with each other will effect a rigid
coupling. A spring *k*, coiled upon the front 55
end of the rod *d* and acting upon the bolts
a, is provided to bring the hooks tightly to-
gether. The uncoupling is effected by turn-
ing the shaft *o* in the direction of the arrow
by means of a chain-wheel *m* and a chain *u*, 60
passing over a guide-roller *n*, whereby the le-
ver *h h'* is turned and the short arm *h* of this
lever pressed against the U-shaped arm *c*,
whereby this, and with it the coupling-hook
b, after overcoming the spring-pressure is 65
pressed forward in a horizontal direction,
Fig. 3. Upon further turning the shaft *o*,
and with it the double-arm lever *h h'*, the
latter engages with the U-shaped arm *c* from
the side (see Fig. 4) and supported by the 70
stiffening-brace *v* forces this arm, and with
it the coupling *b*, also in a lateral direction,
whereby the uncoupling is effected. If now
the shaft *o* be turned to its original position,
the spring *k* will press the coupling-hook, as 75
well as the lever *h*, again into the position
of rest.

The U-shaped arm-shackle *c* is so mount-
ed that it will permit of a resilience of the
coupling-hooks *b* in both directions. The 80
side springs *p* and *q* serve as guides for the
coupling-hooks *b*. The arrangement of a
ratchet-wheel *s* and a pawl *t* upon the shaft
o permits of the coupling-hooks *b* being re-
tained in the uncoupled position. 85

What I claim, and desire to protect by Let-
ters Patent of the United States, is—

In an automatic coupling device with hori-
zontally-oscillating hooks, the combination
with the coupling-hook *b*, of a rod *d* to which 90
the said hook is articulately attached and ar-
ranged to longitudinally slide in a slot of the
same, a U-shaped inclined shackle-arm *c* rig-
idly connected to the said hook *b*, a stiffen-
ing-brace *v* of suitable length connecting the 95
said hook *b* to the said arm *c*, a rotatable
double-arm lever *h h'*, arranged to engage
behind the arm *c* and adapted to be turned

from the side of the car, in such manner that
by the rotation of the said lever upon the
uncoupling of the car, the hook may be moved
forward within the slot of the rod and subse-
5 quently turned in a lateral direction, essen-
tially as and for the purpose set forth.

In witness whereof I have hereunto signed

my name, this 16th day of June, 1902, in the
presence of two subscribing witnesses.

FRANZ KÖHN.
